UNITED STATES PATENT OFFICE.

BENJAMIN F. ROGERS, OF CAMBRIDGE, MASSACHUSETTS.

DESIGN FOR POST-OFFICE BULLETIN-BOARD.

Specification forming part of Design No. 5,229, dated August 22, 1871.

To all whom it may concern:

Be it known that I, BENJAMIN F. ROGERS, of Cambridge, in the county of Middlesex and State of Massachusetts, have invented a certain new and original Design for a Post-Office Advertising-Card, of which the following is a specification:

Figure 1 in the drawing represents a front view, and Fig. 2 a central horizontal section of my design.

The subject of the present invention is a post-office bulletin-board; and it consists in constructing the board in the form shown, and providing it with a frame, *a*, bars *d d d d* having rabbets, as shown in section, to retain the strips or cards

e e e e, and the blank portions *c c'* for advertising or other matter, substantially as shown.

Having thus described my invention, what I claim as new, and desire to secure by Letters Patent, is—

The design for a post-office bulletin-board, substantially as shown.

In testimony whereof I have signed my name to this specification in the presence of two subscribing witnesses.

BENJAMIN F. ROGERS.
